CLAIM

The ornamental design for a table, as shown and described.

DESCRIPTION

FIG. 1 is a front perspective view of a design for a table according to one embodiment;

FIG. 2 is an end elevational view of the design shown in FIG. 1;

FIG. 3 is a side elevational view of the design shown in FIG. 1, in which the opposite side is a mirror image;

FIG. 4 is a bottom elevational view of the design shown in FIG. 1;

FIG. 5 is a top elevational view of the design shown in FIG. 1; and,

FIG. 6 is an enlarged cross-sectional view of a leg of the table shown in FIG. 1.
